UNITED STATES PATENT OFFICE.

EDDIE C. FILSTRUP, OF BENTON HARBOR, MICHIGAN, ASSIGNEE TO COVEL MANUFACTURING COMPANY, OF BENTON HARBOR, MICHIGAN, A CORPORATION OF MICHIGAN.

SAW-GRINDING MACHINE.

1,260,974.

Specification of Letters Patent. Patented Mar. 26, 1918.

Application filed March 17, 1915. Serial No. 14,898.

To all whom it may concern:

Be it known that I, EDDIE C. FILSTRUP, a citizen of the United States of America, and resident of Benton Harbor, Berrien county, Michigan, have invented a certain new and useful Improvement in Saw-Grinding Machines, of which the following is a specification.

My invention relates to improvements in machines for grinding and sharpening saws and the like, and has more particular reference to improvements in a machine of this character by which the operation of sharpening saws is accomplished automatically.

One of the objects of my invention is to provide a machine of this character which will be simple, durable and reliable in construction, and effective and efficient in operation. Other objects of my invention will appear hereinafter.

My invention consists in the features of novelty exemplified in the construction, combination and arrangement of parts herein-after described, illustrated in the accompanying drawings, and more particularly pointed out in the appended claims.

Referring to the drawings—

Figure 1 is a view in front elevation of a saw grinding machine, embodying my invention.

Fig. 2 is a plan view of the structure shown in Fig. 1, taken substantially on the line 2—2 of Fig. 6.

Fig. 3 is a left hand side elevation of the structure shown in Fig. 1.

Fig. 4 is a right hand side elevation of the structure shown in Fig. 1.

Fig. 5 is a view in rear elevation of said machine, substantially on the line 5—5 of Fig. 2, some of the parts being shown in section.

Fig. 6 is a view looking at the front of the machine, but with some parts removed or broken away or shown in section to more closely disclose the parts which this view is more particularly intended to illustrate.

Fig. 7 is an enlarged fragmentary front view of the grinding mechanism and saw feeding parts.

Fig. 8 is a plan view of the structure shown in Fig. 7, the grinding wheel being removed and its support being shown in section.

Fig. 9 is a detail of the gear shifting mechanism through the medium of which the saw

supporting mechanism is raised and lowered by power from the pulley wheel shaft at the rear of the machine.

It will be obvious to one skilled in the art, after having obtained an understanding of my invention from the disclosures herein made, that my invention is capable of modification without departing from the scope and spirit of the claims, and I desire it to be so understood. The machine which I have illustrated in the drawings, and which I have chosen to illustrate my invention, is designed more particularly for the purpose of grinding or sharpening the teeth of large circular saws which are used in lumber mills and the like. This machine is arranged so that the circular saw may be fastened in position thereon and the machine will automatically position the teeth of the saw with respect to the grinding mechanism and operate to sharpen or grind these positioned teeth, these operations being carried out preferably in one continuous operation and at the maximum rate of speed under the particular conditions.

The machine shown in the drawings has a frame A upon which the saw and the operating parts are mounted. This frame, in general, is substantially rectangular in form, has four legs at its corners and a flat table or bed A' at its top. At its front, the frame carries an adjustable saw carriage B. This saw carriage embodies a transversely positioned beam or member 1 which is supported adjacent its ends by two vertically disposed threaded shafts 2 positioned adjacent the two front legs of the frame and journaled in suitable bearings at their upper and lower ends. These threaded shafts operate in elongated correspondingly threaded sleeves 3 carried by the rear face of the carriage beam 1 so that by the rotation of these shafts in the proper direction the beam may be raised and lowered, as desired, to adjust the saw with respect to the grinding mechanism. In the lower part of the frame is a horizontal shaft 4 connected by bevel gears 5, or otherwise, to the lower ends of the vertical shafts 2, whereby these shafts will rotate in unison in the corresponding direction to raise and lower the carriage beam 1. One of the shafts 2 at its upper end carries a suitable hand-wheel 6 by which the shaft may be rotated to adjust the carriage. This provides a convenient means

80

by which the finer degrees of vertical adjustment may be obtained after the saw carriage has been raised or lowered to approximately the proper adjustment by power mechanism, which I will now describe. The rear legs of the frame have outstanding arms 7 supported at their ends, the main driving shaft 8 carrying pulleys 9 which may be connected to any suitable source of power for driving the machine. This shaft carries a loose pulley 9^a adjacent pulley 9 so that the driving belt may be shifted to the pulley 9^a. A gear 10 is attached to and driven by the pulley 9^a. On the arm 7, adjacent the gear 10, is another bearing 11 carrying the short shaft of a gear 12, which is spaced from the gear 10. A triangular frame 13 is pivoted at one of its corners on the shaft of gear 12, and at each of its other corners carries similar gears 14, which, by the pivotal movement of the triangular member 13, are adapted to be shifted into and out of mesh with the gears 10 and 12. Thus the gear 12 may be driven in either direction, depending upon which of the gears 14 is shifted in mesh with said gears 10 and 12. The power in either direction from the gear 12 is transmitted forwardly to the horizontal shaft 4 by a chain 16 which travels 30 around sprockets on said shaft 4 and on the shaft of gear 12. In this manner, the operator may throw one of the gears 14 into mesh with the gear 10 and thereby drive the vertical shafts 2 in the direction corresponding to the direction in which it is desired to move the carriage beam 1. In this machine, I provide a bell crank lever 17 pivoted at one side of the table or bed of the frame. One arm of this bell crank is pivotally connected to a link 18 which is also connected to the triangular member 13 carrying the gears 14. The other arm of said bell crank lever is formed so as to be conveniently handled by the operator. On the 40 carriage beam 1 is a saw supporting block 19 which has a dove-tail sliding connection with the beam 1 for the purpose of horizontal adjustment of the saw. This block is adapted to be moved in either direction 45 along the beam 1 by a threaded horizontally disposed shaft 20 journaled at its ends in suitable bearings on the beam 1. This shaft passes through and is in threaded engagement with a suitably threaded bore in the block 19 for this purpose. The shaft 20 may be rotated in any suitable manner; and in this construction I have shown a short shaft 21 connected with the shaft 20 by the bevel gears 22, and disposed at right angles 50 to the shaft 20 so that a hand crank may be attached to the rear end of the shaft 21 for the purpose of rotating the shaft 20. This particular driving arrangement is provided, in this machine, so that in the event that the 55 particular saw being ground is of large size

and extends beyond the end of the carriage beam, it will not interfere with the operation of the adjusting crank. This supporting block 19 extends somewhat above the beam 1 and at its upper end carries a hollow circular head or member 23 into which is threaded a large bushing 24. This bushing, as seen clearly in Fig. 4, forms a flat face against which the saw to be ground may be positioned, and it is threaded into the circular member 23 so that it may be adjustable to position the periphery or toothed edge of the saw accurately with respect to the grinding mechanism, thus allowing for different sizes and thicknesses of saws. Outstanding from the center of this circular member and rigidly fastened thereto is a threaded stud 25 which is intended to pass through the central hole generally found in saws of the circular type, and also to provide means for holding a couple of clamping nuts 26 by which the saw may be firmly and positively clamped against the face of the bushing 24, and still permit the rotation of the saw when it is being fed to the grinding mechanism. In the lower part of the frame is a horizontal shaft 27 extending from front to rear of the machine, and pivotally mounted on this shaft toward the rear of the machine is a long arm or member C, which, for convenience, I term the saw feeding arm. This feeding arm, as shown more particularly in Figs. 1, 3 and 6, extends diagonally upward toward the front of the frame, and just below the bed plate A¹ of said frame, it turns vertically and passes up through the suitable slot or opening in said bed plate A¹. This feeding arm carries at its upper end a feeding head, and is adapted to be oscillated or reciprocated about its pivot point on the shaft 27 to feed the saw in a step-by-step movement with respect to the grinding mechanism. This feeding arm carries a slidable bearing block 29 having a dove-tail or other suitable connection with the arm C so that it may be vertically shifted along said arm. The bearing block carries an anti-friction roller 30 which is eccentrically mounted for the purpose of adjustment to take up the wear on the parts, and which bears against a shorter arm 31. This shorter arm is pivotally mounted at its lower end on a shaft 32 and is rocked about its pivot by a cam 33 against which it bears at its upper end portion. The arm or lever 31 carries an anti-friction roller 34 which actually takes the thrust from the cam and which is eccentrically mounted so that it may be adjusted to take up the wear on the parts. The cam 33, which for convenience I term a feeding cam, is carried on a shaft 35, which carries at its rear end a bevel gear 36 through the medium of which it derives power from another shaft 37 horizontally positioned at the rear of the frame, the shaft 37 having a 130

bevel pinion 38 which meshes with and drives the bevel gear 36. This shaft 37 derives its power from the main shaft 8 through the medium of a belt 39 which passes around 5 pulleys 40 and 41 on the respective shafts. The cam 33, acting through the auxiliary arm 31, the bearing block 29 and the main feeding arm C, determines, so to speak, the stroke or throw of the upper end of the arm 10 C. The shape of the cam thus determines the approximate adjustment of the feeding arm C, and by employing different shaped cams the proper operation of the feeding arm for any particular type of saw tooth 15 may be determined. Accuracy of adjustment, however, in a machine of this character is an essential function, and the finer adjustments to meet this requirement are accomplished through the arrangement of the 20 arms and bearing block. The bearing block 29 is shiftable toward and away from the pivotal points of the auxiliary and main arms, 31 and C respectively. For instance, as the point of contact of the bearing block 25 with the auxiliary arm 31 approaches the pivotal point (the shaft 32) of said auxiliary arm, the less would be the movement imparted to the bearing block. This decreased movement of the bearing block is, of 30 course, imparted to the bearing arm C. The shifting of the bearing block toward the pivot of the arm 31 also shifts it closer to the pivot of the arm C, and the movement of the upper end of the arm C would ordinarily 35 be amplified. But this increase of movement of the upper end of the arm C is more than offset by the decrease of movement imparted to the bearing block by the auxiliary arm 31, hence the nearer the bearing block 40 is to the pivotal points of the arms 31 and C, the less will be the range of movement of the upper or saw feeding end of the arm C. In this manner the shifting of the bearing block relatively to the pivots of arms 31 and 45 C determines with extreme accuracy the throw or adjustment of the saw-feeding parts at the upper end of the arm C. Any suitable means may be employed for shifting the bearing block. The feeding arm C, 50 of course, is positively moved on its forward or feeding stroke by the cam 33, but on its return stroke it is moved by means of a spring C¹ one end of which is anchored to an outstanding arm C² on the frame, and the 55 other end of which is fastened at C³ on said arm C. In the present structure I have shown a threaded shaft 42 passing through a suitably threaded sleeve on the bearing block 29 and also journaled in a fixed bearing 43 near the upper end of the arm C. This shaft may be rotated in either direction by a hand wheel 44 positioned at the upper end of the feeding arm C and connected to the threaded shaft 42 by means of the shaft 60 65 45 and the universal joint 46 (see Fig. 3).

The saw, a portion of which is indicated in Figs. 6, 7 and 8 by the dotted lines 50, is positioned so that its periphery or toothed edge projects slightly above the top of the bed plate A¹ of the frame so that its teeth 70 will be in position to be engaged by a feeding pawl 51 carried by the upper end of the feeding arm C. This feeding pawl is carried on the end of an arm 52, which, as shown more clearly in Fig. 7, is pivoted on 75 a block 53 which is slidably mounted in a suitable guideway in the upper end of the arm C. This block may be adjusted by a threaded member 54 having a hand-wheel 55. By this construction the range of movement of the feeding pawl may be shifted so that it will accurately position the teeth of the saw with respect to the grinding wheel D. This feeding pawl has a forwardly turned end 56 which, as clearly shown in 80 Fig. 7, is adapted to successively engage the teeth of the saw and rotate the saw about its center, a tooth at each step or stroke. In order to prevent the pawl from feeding too far, the end of arm 52 is arranged to engage 85 a limit stop 52^a on its forward stroke. This stop is carried on the end of a shank which is slidably mounted in a guideway 52^b. The rear end 52^c of said shank is beveled and is arranged to be engaged by an inclined adjusting bolt 52^d having a hand-wheel 52^e by which it may be manipulated. Thus by operating the hand-wheel 52^e the limit stop 52^a may be accurately positioned or adjusted, as 90 desired. It is adapted, when on its forward 95 or feeding stroke, to rest of its own weight in engagement with the teeth of the saw, but on its return stroke the pawl is lifted out of engagement and free from the teeth so as not to drag over the teeth and dull 100 them. In this construction, the pawl is lifted on its return stroke by an arm 57 (see Figs. 3 and 7), one end of which is fastened to a shaft 58 on the top of the bed plate A¹, and the other end 59 of which is curved to present a curved bearing surface to the underside of the pawl 51 and lift said pawl. This arm is actuated by a suitable cam 60 on the shaft 35, through the medium of the arms 61 and 62. The arm 61 is pivotally mounted 110 at its upper end on the shaft 58, and carries at its lower end an anti-friction roller which rides on a cam 60. The arm 62, however, is keyed to the shaft 58 so as to operate the lifting arm 51, and it receives its movement 115 from the arm 61 through the bearing screw 63, this screw 63 being carried in the lower end of the arm 62 which is curved around and positioned in the path of the arm 61. This construction provides a convenient adjustment between the arms 61 and 62, so that the operation of the lifting arm 61 may be 120 carefully controlled. 125

The grinding mechanism is supported or mounted upon a frame or carriage 65 which 130

is shiftable or slidable up and down in a suitable support or guiding structure 66 upstanding from the bed plate of the machine, a portion of this guiding structure depending below the bed plate of the machine. This grinder carriage is reciprocated or oscillated vertically through suitable mechanism actuated by a cam 67 on the shaft 35. This cam operates against an anti-friction roller 68 on a long carriage reciprocating lever E which is mounted on a shaft 69 journaled in brackets in the lower part of the frame and forming a pivot for said lever. This lever curves generally downward so that its other arm occupies a position substantially horizontal in the lower portion of the frame beneath the grinder carriage. This arm carries a sliding block 70 pivotally connected to a link 71, the upper end 10 of which is pivotally connected to the lower end of the grinder carriage, so as to transmit motion from the operating lever E to the grinder carriage. The arm of the lever E, which carries the block 70, is curved on an arc, the center of which is substantially the pivotal point of connection of the link 71 with the grinder carriage, and by shifting the block 70 along the arm to vary the distance between itself and the pivotal center 15 69 of the lever E the length of stroke of the grinder carriage may be accurately governed. The actuation of the block 70, for the purposes of this adjustment, is accomplished by a threaded shaft 72, which is connected by a universal joint 73 to the end of another shaft 74. This shaft 74 is journaled in bearings 75 on the lever E and carries at its outer end a hand-wheel 76 by which it may be manipulated by the operator, the reason for this universal joint connection between the shafts 74 and 72 being to place the hand-wheel 76 in a convenient position for the operator. The grinder wheel D may be of any suitable type for the purpose. In this construction it is carried on a horizontal shaft which is journaled in a suitable bearing 77 on the end of a depending arm 78. The grinder wheel shaft also carries a suitable pulley 79 over which 20 the belt 80 passes for driving said grinder wheel. The supporting arm 78, which carries the grinder wheel, rises to a point above the grinder wheel and then turns horizontally and carries a vertical shaft which is 25 journaled in a vertically disposed bearing 81 mounted on the grinder carriage 65 so that the grinder wheel may be swung or moved bodily to position the grinder at the proper angle with respect to the teeth of the saw. 30 In saws of the character which this machine is more particularly designed to sharpen, the faces of alternate teeth are cut on the same angle and the intermediate teeth are cut on the opposite angle, and the purpose 35 of this construction is to enable the grinder

wheel to be positioned to cut or sharpen the teeth at these angles. In this construction the grinder is alternately turned to the proper angle for the teeth, and this turning or positioning of the grinder occurs before 40 the grinder is brought down by its carriage to the cutting position, these parts being all properly timed with respect to each other. The rocking of the grinder supporting arm 45 78 to position the grinder at the proper angle with respect to the plane of the saw is accomplished through the medium of two segmental gears 82 and 83 which are constantly in mesh. These gears are, as shown in the drawings, comparatively broad faced 50 so that they will always remain in mesh and still permit a considerable relative movement vertically of the grinding wheel carriage. The gear 82 is carried on the grinding wheel supporting arm 78, while the gear 83 is carried at the end of a horizontally swinging arm 84, the pivotal shaft of which is journaled in a bearing post 85 upstanding from the bed plate of the machine. This shaft extends below the bed plate and carries at its lower end another arm 86 by which the gear 83 and its supporting arm 84 are rocked or oscillated. The arm 86 is pivotally connected to a link 87 which extends to the rear of the machine where it is connected by a pin and slot connection 88 to an arm 89. This pin and slot connection 88 permits an adjustment of the link 87 with respect to the pivotal center of the arm 89 so that the length of stroke of the link 87 55 may be conveniently adjusted. This arm 89 is carried on a hub 90 mounted to rock on a depending stud on the underside of the bed plate. This hub carries another arm 92 having at its end a follower 93 adapted to travel in the double grooved cam 94 on the cam shaft 35. The grooves 95 of this cam cross each other at a certain point in the periphery of the cam so as to impart a rocking movement to the arm 92 and this motion 60 is transmitted through the mechanism just described to the grinder wheel. The arm 92, which carries the follower, is made in several pivoted sections so that the follower may be swung up out of the cam groove 65 when the cam is to be changed. The grinder carriage also carries an upstanding bracket 96 upon which are mounted a pair of pulleys 97 for maintaining the belt 80 in proper position relatively to the grinding 70 wheel pulley 79. These pulleys 97 are supported on comparatively long studs 98 outstanding from the bracket 96 and permit considerable lateral movement of the pulleys 97 so that they will automatically adjust 75 themselves to the various angular positions in which the grinding wheel pulley is placed during the operation of the machine. The belt 80 passes around and is driven by a large pulley 99 on a shaft 100 which is sup- 80

ported by upstanding brackets 101 on the rear of the machine frame, and said belt 80 is maintained at its proper tension during the operation of the grinding mechanism 5 by an idler pulley 102 which rests in a bight of the belt and which is carried on the end of an arm 103 pivoted on the shaft 100. The shaft 100 also carries another and smaller pulley 104 which is driven by a belt 105 extending downwardly and around a main driving pulley 106 which is carried by the main shaft 8.

The particular saw which is being sharpened is, as before mentioned, positioned with 15 its teeth slightly above the head plate of the frame. The teeth of the saw being at considerable distance from the center of the saw, which is solidly supported, would be likely to result in considerable vibration of 20 the saw during the grinding operation, were it not for the fact that I provide mechanism which operates to firmly grip the saw at its toothed edge adjacent the portion being operated upon by the grinding wheel. In 25 this construction, I provide underneath the frame a long arm 110 which is pivoted to the frame at 110^a. One end of this arm carries a small adjustable button 110^b which bears against the inner or rear face of the 30 saw adjacent its cutting edge directly beneath the grinding wheel. (See Figs. 7 and 8.) This button is adapted to be adjusted with respect to the saw by a threaded adjustment rod 110^c which is connected with 35 the other end of the arm or lever 110 so that said lever may be swung about its pivot. This adjusting rod 110^c is mounted in a suitable threaded bearing on the underside of the frame and has a hand wheel 110^d by 40 which it may be manipulated. On the opposite side of the saw is a long arm 111 which is pivoted at 112 at the far corner of the frame. The free end of this arm has a flat-headed adjustable button 113 which is 45 adapted to be clamped against the saw and in turn to clamp the saw against the button 110^b to firmly hold the saw in place. The clamping action of this arm is attained by a cam 114 rotatably mounted adjacent the 50 pivot 112 of said arm and acting against a short extension 115 on said arm. This saw clamping mechanism is of sufficient length to permit the largest, as well as the smallest saw, within the range of the machine to be 55 held in place, and its operation is such that it firmly holds the saw against vibration, and at the same time permits the saw to be rotated step by step by the feeding mechanism. This mechanism thus makes a very 60 accurate adjustment of the saw with respect to the grinding wheel and at the same time provides a very rigid clamping means which rigidly holds the saw against vibration without interfering with the rotation of the 65 saw.

It will thus be observed from the foregoing that I have provided a machine which is readily and conveniently adjustable in all of its parts, and which, by reason of the arrangement and adjustability of its parts, is 70 capable of being used for a wide range of saws, including various sizes and thicknesses and the character of the teeth. Practically the only parts which need to be changed for different species of saws are the cams, and 75 it will be particularly noted that these cams are, for this reason, mounted upon a single readily removable shaft positioned at the side of the machine near the top thereof, so as to be readily and conveniently accessible 80 to the operator, this being in contradistinction to the present machines now on the market in which the cams are located within the frame in the lower portion thereof, making it difficult and tedious to remove or replace the cams when desired. Furthermore, in my present invention the cams are mounted at the upper side of the machine so that they will not be subjected to the filings or grindings which fall from the grinder 85 wheel. But as a further precaution, I provide a chute F on the grinder carriage supporting frame 66, this being in position to receive the grindings from the grinder wheel and convey them downwardly beyond 90 the reach of the operating mechanism of the machine.

What I claim as my invention is:

1. The combination of a frame, saw supporting means thereon, a reciprocating carriage, a grinder wheel carried thereby and arranged for movement on a vertical axis to present the grinder at different angular positions with respect to the saw, a pair of gears constantly in mesh while the carriage 100 reciprocates for placing the grinder wheel in its different positions, one of said gears being connected with said carriage and means for actuating the other gear.

2. The combination of a moving carriage, 110 a grinder wheel, a supporting member for said grinder wheel mounted on and movable with said carriage, a broad-faced gear carried by said supporting member, a second broad-faced gear meshing with said first 115 gear, and means for actuating said second gear to transmit motion to the first gear and supporting member while the carriage moves.

3. The combination of a reciprocating 120 carriage, a rotary arm on said carriage, a grinder wheel carried by said arm, a broad-faced gear connected with said arm, a second broad-faced gear meshing therewith for transmitting rotary motion to said arm, and 125 means for actuating said second gear.

4. The combination of a saw supporting mechanism, a pair of pivoted arms, means for actuating one of said arms, a bearing member shiftable relatively to both of said 130

- 6 arms for transmitting motion from said actuated arm to the other arm, and means carried by said other arm for rotating the saw upon its support.
- 5 5. The combination of means for supporting a saw for rotary movement, a movable member, a pivoted arm, a member for transmitting motion from said movable member to the arm and shiftable relatively to both 10 said member and arm toward and from the pivot point of said arm to vary the degree of movement imparted to the arm, means for actuating said movable member, and means carried by said arm for engaging the 15 teeth of the saw to rotate the saw.
6. The combination of a reciprocating feeding mechanism, and means for actuating said feeding mechanism, comprising a pair of pivoted arms, means for oscillating one 20 of said arms about its pivot, and a bearing member for transmitting motion from said oscillated arm to the other arm and shiftable longitudinally toward and from the pivotal points of both of said arms to vary 25 the degree of movement imparted to the said other arm.
7. The combination of a reciprocating feeding mechanism, a pivoted arm connected at one end to said reciprocating mechanism, 30 a shorter pivoted arm, a cam for oscillating said shorter arm, and a bearing block for transmitting power from the shorter arm to the longer arm, and means for shifting the bearing block longitudinally of said arms 35 relative to the pivotal centers of both of said arms to vary the degree of reciprocation of said reciprocating mechanism.
8. The combination of a frame, a cam shaft supported by said frame at the upper 40 side thereof, a saw supporting mechanism, an upright arm substantially below the top of said frame pivoted at its lower end and having means at its upper end for periodically rotating said saw, a cam on said shaft 45 for actuating said arm, a grinder mechanism and a carriage for vertically reciprocating said grinder mechanism, actuating mechanism below said frame top for reciprocating said carriage, and a cam on said shaft for driving said actuating mechanism.
9. The combination of a frame, a saw feeding mechanism substantially below the top of said frame, a saw grinding mechanism above the top of the frame, mechanism 55 for positioning said saw grinding mechanism located beneath the top of the frame, a single shaft mounted at the side of said frame but beneath the top thereof in a conveniently accessible position, a plurality of 60 removable cams on said shaft for actuating said mechanisms, and means for driving the shaft.
10. The combination of a frame, a beam supported on said frame, means for raising 65 and lowering said beam vertically, a block shiftable horizontally on said beam, a saw supporting device carried by said block and adjustable at right angles to said vertical and horizontal movements of said beam and block.
11. The combination of a frame, a horizontal beam mounted and movable vertically on said frame and having means for supporting the saw, mechanism for raising and lowering said beam, a source of power, 70 and a reversible clutch for connecting said mechanism with and disconnecting it from said source of power.
12. The combination of a frame, a horizontal beam having a horizontally movable saw support thereon, threaded shafts supporting said beam and adapted to be rotated to bodily raise and lower the beam, a main shaft, manually controlled mechanism for transmitting power from the main shaft 75 to said threaded shafts, and means for moving the saw support on the beam.
13. The combination of a frame having saw supporting means, and saw clamping mechanism for gripping the saw adjacent its periphery and embodying a long arm pivoted at one end, and a cam acting against said arm at its pivoted end to press the free end of the arm against the saw.
14. The combination of saw supporting 80 mechanism, a reciprocating member, a pawl carried thereby and adapted to engage the teeth of the saw on the forward stroke, a pivoted lever for raising the pawl clear of the teeth on the return stroke, a cam-actuated arm, and means for relatively adjusting said lever and arm for operating said lever.
15. The combination of saw supporting 85 mechanism, a reciprocating member, a pawl carried thereby and adapted to engage the teeth of the saw on the forward stroke, a lever engaging said pawl, and cam mechanism timed to actuate said lever and raise the pawl on the return stroke thereof.
16. In a saw grinding machine, the combination of a frame, a vertically reciprocating grinder carriage extending above said frame, a grinder mounted on said carriage, mechanism for moving the grinder about a 90 vertical pivot to position it with respect to the saw, an oscillating mechanism for rotating the saw with respect to the grinder, said mechanism extending substantially below the top of the frame, mechanism located entirely below the top of the frame for bodily reciprocating said carriage to move the grinder vertically, a cam shaft located at one side of the frame near the top thereof, a plurality of removable cams on said shaft 95 for actuating said mechanisms, and a source of power connected to said cam shaft for driving the same.
17. In a saw grinding machine, the combination of a frame, saw grinding mecha- 100

nism mounted thereon, means supporting the saw for rotary movement, a lever pivoted at one end and carrying at its upper end a pawl for engaging the saw teeth, a 5 second lever pivoted at one end and disposed in juxtaposition to said first mentioned lever, a cam engaging the other end of said second lever to oscillate the same about its pivot, and a bearing block positioned between the levers and adjustable lengthwise 10 of both levers for transmitting the oscillating movement of the second lever to the first lever.

18. In a saw grinding machine, the combination of a frame, a saw supporting device, a saw grinding mechanism disposed in the upper portion of said frame, an oscillating arm pivoted in the lower portion of said frame and extending upwardly to 15 the top thereof, a pawl carried by the upper end of the arm for engaging the saw teeth, a cam actuated arm pivoted at one end, a 20 slideable bearing block on the oscillating arm engaging the cam actuated arm, and 25 means for adjusting the bearing block on the said oscillating arm toward and from the pivotal points of both of said arms to regulate the stroke of the pawl carrying oscillating arm.

30 19. In a saw grinding machine, the combination of a frame, a support for the saw, grinding mechanism for the saw, a pair of juxtaposed arms pivoted at corresponding ends to said frame, cam mechanism for oscillating one of said arms, a member for transmitting the motion of said arm to the other arm, means for shifting said member longitudinally of both arms and relatively 35 to the pivotal points of both arms to regu-

late the stroke of said other arm, and a pawl 40 on said other arm for rotating the saw relatively to the grinding mechanism.

20. In a saw grinding machine, the combination of a frame, a vertically reciprocating grinder carriage at the top of said 45 frame, a lever pivoted in the lower portion of the frame and having one of its arms disposed generally horizontally and its other arm extending generally upwardly, a pitman pivotally connected to said carriage 50 and to the horizontal arm of said lever, means for adjusting the connection of said pitman with the lever toward and from the pivotal point of said lever to vary the stroke of the reciprocating carriage, and cam mechanism 55 actuating the other arm of said lever and located in the frame at one side thereof near the top.

21. In a saw grinding machine, the combination of a frame, a vertically reciprocating grinder carriage, grinder mechanism supported on said carriage and vertically movable therewith and mounted to turn about a pivotal axis to change the angular 60 relation of the grinding mechanism with respect to the saw, a segment gear on said grinding mechanism vertically movable therewith, a segment gear on the frame, said gears being in mesh and having their teeth disposed parallel to the vertical movement 65 of said grinding mechanism, and means for actuating said second gear.

Signed by me at Chicago, Illinois, this 26th day of February 1915.

EDDIE C. FILSTRUP.
